UNITED STATES PATENT OFFICE

160,925

CAMERA

Arthur H. Crapsey, Jr., Rochester, N. Y., assignor
to Eastman Kodak Company, Rochester, N. Y.,
a corporation of New Jersey

Application July 27, 1949, Serial No. 4,161

Term of patent 14 years

(Cl. D61—1)

To all whom it may concern:

Be it known that I, Arthur H. Crapsey, Jr., a citizen of the United States, residing in Rochester, in the county of Monroe and State of New York, have invented a new, original, and ornamental Design for Cameras, of which the following is a specification, reference being had to the accompanying drawings, forming a part thereof, in which:

Fig. 1 is a top plan view of a camera with the lens mount extended, showing my new design;

Fig. 2 is a perspective view of the camera shown in Fig. 1, also showing a part of the top and end walls and the front wall of a camera of my new design;

Fig. 3 is a perspective view taken from the rear showing portions of the top and side walls and

showing the rear wall of a camera embodying my new design; and

Fig. 4 is an end elevation of the camera shown in the preceding figures.

I claim:

The ornamental design for a camera, as shown.
